KEEPER LINK

Joseph F. Jelinek, Minneapolis, and Emmet O'Reilly, St. Paul, Minn., assignors to St. Paul Hydraulic Hoist Company, Minneapolis, Minn., a corporation of Michigan

Application November 1, 1940, Serial No. 363,890

3 Claims. (Cl. 16—169)

This invention relates to improvements in keeper links or devices for use in releasably retaining pivot or fastening pins in place in the supporting parts.

Such devices are used for quickly and releasably retaining such pins in place and supplant the more conventional nuts, cotters, and the like which are slow in operation and generally require the use of tools in their installation or removal.

The primary object of our invention is to provide a device of this kind which will be simple, capable of convenient application or disconnection from the pin and which will nevertheless provide a secure and safe fastening means for the pin.

Another object is to provide a link of this kind to act as a keeper for the pin and which is so constructed as to have sufficient resiliency to provide a continuous grip upon the pin but to permit convenient removal without tools when desired.

These and other more detailed and specific objects will be disclosed in the course of the following specification, reference being had to the accompanying drawing, in which—

Fig. 1 is a perspective view of a truck body and end gate showing our keeper link in use for retaining a hinge pin for the gate in place.

Fig. 2 is an enlarged fragmentary plan view of the hinge structure showing the keeper in place.

Fig. 3 is a side elevation of a pin prepared for the use of our keeper.

Fig. 4 is a plan or elevational view of the keeper or link alone.

This application is a continuation in part from our copending application for United States patent on a Convertible end gate hinge, filed April 13, 1940, under Serial No. 329,440. Reference is invited to this application for a complete disclosure of the hinge mechanisms for the end gate.

Referring now more particularly and by reference characters to the drawing, A represents a truck body (only the rear end portion of which is shown) having rear corner posts B defining a dumping opening C which is adapted to be closed by the end gate D. Said end gate may hinge either from lower, combination latch and hinge units E or from upper hinge mechanisms F as has been fully disclosed in our copending application hereinabove identified.

The said upper hinge mechanisms F each includes a bracket G having spaced sides H to re-

ceive the link bars I which connect to the gate D, and registering apertures J are provided in the parts H and I to selectively receive a pivot or hinge pin K. Said pin must be capable of being conveniently shifted between front and rear apertures J in the operation of the gate and, of course, must be secured against dislodgement from said apertures when adjusted therein.

In accordance with the present invention the pins K each have a head 5 at one end of its rounded shank portion 6 and at the opposite end a circumferential groove 7 is provided in such position that it will just fall outwardly clear of the bracket side H through which this end of the pin projects as shown in Fig. 2.

Our keeper device or link is designated generally at 8 and as shown is substantially "pear-shaped" having a rounded, bight or eye end or portion 9, a larger rounded loop end or portion 10 and connecting, substantially parallel leg or side portions 11. The link is made from spring wire, rod, or similar material and a length of such material is bent back on itself to provide the eye end 9, then the leg or side portions 11 and finally the larger loop end 10. The ends 12 of the material forming the loop 10 are left free and overlap as clearly indicated for a purpose which will presently appear.

The internal diameter of the eye end 9 is slightly greater than the diameter of the groove 7 in the pin K whereas the spacing between the leg or side portions 11 is slightly less than this diameter of the groove. The loop end 10 is of course considerably larger in diameter than the pin.

The link is bent substantially at the junction 13 of one leg portion 11 with the eye end 9 and at the other side substantially at the junction 14 of the other leg portion and the loop end 10 as best seen in Fig. 2. As a result, the loop end 10 stands angularly to the plane of the eye end 9 and this "staggering" of these, in effect, offsetting bends enables the partially curved ends 12 of the link to nicely overlie each other in the formation of said loop end 10.

A tie chain or similar flexible fastener 15 connects the loop end of each link 8 to the corner posts B of the truck body to permit sufficient freedom for manipulation of the links but to prevent their loss or misplacement.

In use the pin K is placed in the desired position and the keeper link 8 is then engaged therewith by slipping the eye end 9 into the groove 7 so that this end of the link overlies the bracket side H around the end of the pin and prevents

its dislodgement. In this position the loop end 10 of the link stands outward at an angle to the bracket side as clearly shown and thus permits the convenient manipulation of the link with the hand. The diameter of the eye end 9 as described is such that it will retain its engagement with the groove 7 and the narrow space between the side or leg portions 11 will prevent disengagement by the accidental endwise shifting of the link.

To thus engage the link the pin end may be introduced into the loop end 10 and then by a pull on this end the leg portions 11 may slide through the groove until the eye end 9 comes to rest encircling said groove. Opposite movement of the link will free it from the pin and it will be evident that the freedom for transverse springing movement (in the plane of the leg portions 11) due to the parted overlapped ends 12 of said loop 10 will facilitate this operation.

The parted overlapping ends 12 also make it possible to spread the leg portions 11 of the link simply by grasping the loop end 10 and urging said ends 12 relatively together as will be clearly evident. This operation will make it possible to engage the link with the pin without the aforesaid endwise movement or will greatly facilitate this operation.

It is to be understood of course that our link device may be used wherever a quick, convenient and positive type of keeper of this kind may be desired.

It is understood that suitable modifications may be made in the structure as disclosed, provided such modifications come within the spirit and scope of the appended claims. Having now therefore fully illustrated and described our invention, what we claim to be new and desire to protect by Letters Patent is:

1. A keeper link for engaging a circumferentially grooved pin, comprising a partially round bight portion adapted to engage the groove in the pin, side portions extending from the extremities of the bight portion and terminating in rounded ends defining a partially round loop portion, and the said side portions being bent angularly with respect to the plane of the bight portion and at relatively different points with respect thereto, whereby the loop end will be angularly disposed and to cause one of the rounded ends defining said loop to overlie the other.
2. The combination with a hinge structure including a hinge member and a pin extended outwardly through one side thereof and provided with a groove in its extended end portion, of a locking link comprising an end larger in diameter than the pin and a relatively narrow extended end portion adapted for frictional engagement with the groove in the pin, a flexible member connected to the larger end of the link, and the said link being bent between its ends to cause the larger end to stand outward from said hinge member when the narrow end portion is engaged with the groove in the pin.
3. A keeper link for engaging a grooved pin, comprising a partially circular end adapted to engage the groove in the pin, side members extending from the extremities of the partially circular end and terminating in rounded end portions defining a partially circular loop greater in diameter than the pin, and the said rounded end portions being overlapped where they define the loop to thereby permit the side portions of the link to be spread apart by relative movement of said end portions.
